FORMER DEVICE FOR MAKING PAPER
PULP CONTAINERS

Raymond E. MacDonald, Westwood, Mass., assignor of one-half to Edwin M. Warwick, Walpole, Mass.

Application March 6, 1943, Serial No. 478,260

11 Claims. (Cl. 92—57)

This application is a continuation in part of one filed by me August 21, 1939, Serial No. 291,146.

This invention relates to a former device that is used to form a container of wet paper pulp having an integral bottom and side structure.

The principal object of my invention is to so construct such a former device that the deposit of the wet paper pulp on my device will be uniform and compact and that at a critical point, such as where the bottom and side merges, the deposit will be firm and strong enough to withstand the finishing operations the container has to undergo while the paper pulp is still soft. Another object is to make such a device that is simple in construction and durable, and can be easily disassembled sufficiently to clean it.

The foregoing and other objects which will appear as the nature of the invention is better understood, may be accomplished by a construction, combination and arrangement of parts such as is disclosed by the drawing and specification. The nature of the invention is such as to render it susceptible to various changes and modifications, and, therefore, I am not to be limited to said disclosure; but am entitled to all such changes therefrom as fall within the scope of my claims.

In the drawing:

Figure 1 is a longitudinal sectional view of my former device.

Figure 2 is a sectional view taken on the line 2—2 of Figure 1 to show an upper portion of my device including the upper baffle plate.

Figure 3 is a sectional view taken on the line 3—3 of Figure 1 to show the intermediate baffle plate.

Figure 4 is a sectional view taken on the line 4—4 of Figure 1 to show the lower baffle plate.

As illustrated my former device has a conduit 10 connected thereto having a head flange 11 at one end which is fastened to my former device. A spacer ring 13 is between said head flange 11 and a bearing 16. Said spacer 13 has an opening 14 to accommodate a belt 15 that drives a rotatable pulley 20 within said spacer 13. Said bearing 16 has an inner shoulder 17 on which a flange 23 integral with said pulley 20 bears. Bolts 18 extend from said bearing 16 through said spacer 13 and said head flange 11. A rotor member 19 is fixedly connected to said pulley 20 by screws 21 which extend from said rotor 19 into said flange 23 of said pulley, so that as said pulley rotated said rotor 19 is likewise rotated. Said rotor 19 has an extension portion 25 of smaller diameter which provides a circumferential shoulder on which a screen 55, later referred to, bears. With-

in said rotor extension portion 25 an opening or space 24 is formed. A cross-shaped member 26, having four arms 26a thickened at their end portions, is fastened to said rotor 19 by screws 27. Intermediate portions of said arms 26a are recessed as at 30. A screw-threaded hole 28 is provided in the center of said cross-shaped member 26 to receive the screw-threaded end of a supporting rod 32. Commencing with said recesses 30, then to 10 spaces 31 between said arms 26 and to said opening 24, an open passage is provided through to said conduit 10 as shown in Figure 1 of the drawing. This is the path of the suction draft created by exhaustion of the air from the interior of my device and connected parts.

Mounted on said supporting rod 32 is an upper baffle plate 33 having a plurality of holes 34 therein and a hub 35. There are spaces 30 and 31 between this baffle plate 33 and said arms 26a that provide the afore-mentioned air passage or path. At an intermediate portion of said rod 32 an intermediate baffle plate 37 is mounted thereon having holes 38 therein and a hub portion 39. It will be noted that said holes 38 are farther from 25 the center point of said baffle plate 37 and the longitudinal or vertical axis of my device than said holes 34 are from the center point of said baffle plate 33 and said axis.

On the lower portion of said rod 32 is a lower baffle plate 41 which consists of an upper part 42 having a hub 43 and holes 44 which are nearer to the center of said baffle plate 41 and to said axis than any of said holes 34 and 38 are to the center of their baffle plate. There are also 30 smaller and more numerous holes 45 nearer the periphery of said upper part 42 which are spaced farther from the center point of said baffle plate 41 and said axis than said holes 38 are from the center point of said baffle plate 37. Said lower baffle plate 41 has a lower part 47 the under surface of which as shown in Figure 1 of the drawing is concaved as at 48. Said lower part 47 has a hub 49, and it also has holes 50 which are in alinement with said holes 44. Screws 51 hold 40 said upper part 42 and lower part 47 together; but spaced apart at their outer portions to leave space 52. At the periphery of said lower part 47 holes 54 extend inwardly and communicate through said space 52 with said holes 45. Immediately adjacent and in communication with said holes 54 grooves 53 are cut part way into and 45 extend to the bottom surface of said lower part 47. Said holes 54 and grooves 53 bring the path of the vacuum directly to the point where the 50 bottom and side of the container merge, which is

a critical portion of the container where there must be certain strength. This construction assures that the wet paper pulp will be uniformly drawn onto the screen at this point and with considerable force to insure tight packing of the material. Said holes 45 and 54 are equal in number.

A screen 55 forms an outside portion of said device, extending from and covering the bottom and side up to said extension portion 25 of said rotor 19 being held in place on said baffle plates by wires 56. As said rotor is rotated by said pulley 26 my former device is likewise rotated. Portions of my device above the upper baffle plate 43 constitute the top of said device.

In operation my former device is inserted into a tank containing wet paper pulp, not shown, a suction force is created by any well known means such as a vacuum tank connected to said conduit 10 and the force of the suction created by exhausting the air starting at the bottom of my former device draws wet paper pulp onto said screen, a portion being shown marked P in Figure 1 of the drawing.

It will be noted that said lower baffle plate has holes nearer to the periphery and farther from its center point and said axis than either of the other two baffle plates 37 and 33. The effect of this is to have the suction force nearer the outer surface of my device because the force of the suction becomes lesser the farther from the source that creates it. The holes in the baffle plates are located progressively nearer to said longitudinal axis towards the upper end of said former device because the suction force is progressively greater the nearer it gets to its source.

What I claim is:

1. A former device for making containers of wet paper pulp comprising three baffle plates spaced apart and having openings therein that are spaced apart, a screen associated with said baffle plates, and forming an outer portion of said device, said baffle plates extending laterally the full transverse area of said screen and being imperforate except for said openings, and top means having a central opening in communication with said openings, the said openings in the intermediate baffle plate being farther from the longitudinal axis of said device than said openings in the upper baffle plate, the lower said baffle plate having openings farther from said longitudinal axis of said device than said intermediate baffle plate openings.

2. A former device for making containers of wet paper pulp comprising a supporting rod an interior portion of which is solid, three baffle plates mounted thereon spaced apart and having openings therein that are spaced apart, a screen associated with said baffle plates and forming an outer portion of said device, said baffle plates extending laterally the full transverse area of said screen and being imperforate except for said openings, and top means having a central opening in communication with said openings, the said openings in the intermediate baffle plate being farther from the longitudinal axis of said device than said openings in the upper baffle plate, the lower said baffle plate having openings farther from said longitudinal axis of said device than said intermediate baffle plate openings.

3. A former device for making containers of wet paper pulp comprising three baffle plates spaced apart and having openings therein that are spaced apart, a screen associated with said baffle plates and forming an outer portion of said

device, said baffle plates extending laterally the full transverse area of said screen and being imperforate except for said openings, and top means having a central opening in communication with said openings, the said openings in the intermediate baffle plate being farther from the longitudinal axis of said device than said openings in the upper baffle plate, the lower said baffle plate having openings farther from said longitudinal axis of said device than said openings some of which commence at the periphery thereof.

4. A former device for making containers of wet paper pulp comprising a hollow foraminous body, means having an opening to provide for suction draft at a top portion thereof, said opening being relatively near to the longitudinal axis of said device, a plurality of at least three baffle plates within and extending radially to said body spaced apart and having openings therein arranged to direct the line of suction draft in the longitudinal direction of said screen in a path that is wider at the lower portion of said device than at any other part whereby said line of said suction draft becomes more constricted towards said top portion, the openings in an intermediate baffle plate being farther from the longitudinal axis of said device than the openings in the upper baffle plate, the lower said baffle plate having openings farther from said longitudinal axis of said device than said intermediate baffle plate openings and in communication with an outside opening in said body, said baffle plates being imperforate except for said openings.

5. A former device for making containers of wet paper pulp comprising three baffle plates spaced apart and having openings therein that are spaced apart, a screen associated with said baffle plates and forming an outer portion of said device, said baffle plates extending laterally the full transverse area of said screen and being imperforate except for said openings, and top means having a central opening in communication with said openings, all of said openings in the intermediate baffle plate being farther from the longitudinal axis of said device than said openings in the upper baffle plate, the lower said baffle plate having openings farther from said longitudinal axis of said device than said intermediate baffle plate openings some of which commence at the periphery thereof, said lower baffle plate having grooves at an extremity thereof communicating directly with said peripheral openings.

6. A former device for making containers of wet paper pulp comprising three baffle plates spaced apart and having openings therein that are spaced apart, a screen associated with said baffle plates and forming an outer portion of said device, said baffle plates extending laterally the full transverse area of said screen and being imperforate except for said openings, and top means having a central opening in communication with said openings, all of said openings in the intermediate baffle plate being farther from the longitudinal axis of said device than any of said openings in the upper baffle plate, the lower said baffle plate having openings farther from said longitudinal axis of said device than said intermediate baffle plate openings, the bottom surface of said latter baffle plate being concaved.

7. A former device for making containers of wet paper pulp comprising three baffle plates spaced apart and having openings therein that are spaced apart, a screen associated with said

baffle plates and forming an outer portion of said device, said baffle plates extending laterally the full transverse area of said screen and being imperforate except for said openings, and top means having a central opening in communication with said openings, all of said openings in the intermediate baffle plate being farther from the longitudinal axis of said device than any of said openings in the upper baffle plate, the lower said baffle plate having openings farther from said longitudinal axis of said device than said intermediate baffle plate openings, the peripheral edge of a lower portion of said lower baffle plate having openings therein and an upper portion thereof having openings therein spaced from said peripheral edge and communicating with said peripheral openings.

8. A former device for making containers of wet paper pulp comprising three baffle plates spaced apart and having openings therein that are spaced apart, a screen associated with said baffle plates and forming an outer portion of said device, said baffle plates extending laterally the full transverse area of said screen and being imperforate except for said openings, and top means having a central opening in communication with said openings, said openings in the intermediate baffle plate being farther from the longitudinal axis of said device than said openings in the upper baffle plate, the lower said baffle plate having openings farther from said longitudinal axis of said device than said intermediate baffle plate openings and also having openings therein nearer to said axis than those in the other said baffle plates.

9. A former device for making containers of wet paper pulp comprising three baffle plates spaced apart and having openings therein that are spaced apart, a screen associated with said baffle plates and forming an outer portion of said device, said baffle plates extending laterally the full transverse area of said screen and being imperforate except for said openings, and top means having a central opening in communication with said openings, said openings in the intermediate baffle plate being farther from the longitudinal axis of said device than said openings in the upper baffle plate, the lower said baffle plate having openings farther from said longitudinal axis of said device than said intermediate baffle plate openings and having grooves therein at the outer extremity thereof in communication with said lower baffle plate openings.

10. A former device for making containers of wet paper pulp comprising three baffle plates spaced apart and having openings therein that are spaced apart, a screen associated with said baffle plates and forming an outer portion of said device, said baffle plates extending laterally the full transverse area of said screen and being imperforate except for said openings, and top means having a central opening in communication with said openings, said openings in the intermediate baffle plate being farther from the longitudinal axis of said device than said openings in the upper baffle plate, the lower said baffle plate having openings farther from said longitudinal axis of said device than said intermediate baffle plate openings, the lower baffle plate having an upper portion and a lower portion opposite portions of which have a space between them, said lower portion having openings therein at said peripheral edge in communication with said space, and said upper portion having openings therein spaced inwardly from the peripheral edge and communicating with said space.
11. A former device for making containers of wet paper pulp comprising three baffle plates spaced apart and having openings therein that are spaced apart, a screen associated with said baffle plates and forming an outer portion of said device, said baffle plates extending laterally the full transverse area of said screen and being imperforate except for said openings, and top means having a central opening in communication with said openings, said openings in the intermediate baffle plate being farther from the longitudinal axis of said device than said openings in the upper baffle plate, the lower said baffle plate having openings farther from said longitudinal axis of said device than said intermediate baffle plate openings, said lower baffle plate having an upper portion and a lower portion, opposite portions of which have a space between them, both said portions having openings therein spaced inwardly from the peripheral edge of said lower baffle plate and in communication with each other and nearer to said longitudinal axis than any openings in said upper baffle plate, said lower portion having openings therein at said peripheral edge in communication with said space, and said upper portion having openings therein communicating with said space.

RAYMOND E. MACDONALD.
